UNITED STATES PATENT OFFICE

145,963

DESIGN FOR A LUBRICATING EQUIPMENT CABINET

Francis Lawrence Ayres, Chicago, Ill., assignor to
Stewart-Warner Corporation, Chicago, Ill., a
corporation of Virginia

Application November 16, 1945, Serial No. 123,823

Term of patent 14 years

(Cl. D52—2)

To all whom it may concern:

Be it known that I, Francis Lawrence Ayres, a citizen of the United States, residing at Chicago, in the county of Cook and State of Illinois, have invented a new, original, and ornamental Design for a Lubricating Equipment Cabinet, of which the following is a specification, reference being had to the accompanying drawings, forming part thereof.

Fig. 1 is a perspective view of a lubricating equipment cabinet showing my new design;

Fig. 2 is a side elevational view thereof; and
Fig. 3 is a top plan view thereof.

The back of the cabinet, not seen in the drawings, is similar in appearance to the front thereof.

I claim:

The ornamental design for a lubricating equipment cabinet, substantially as shown and described.

FRANCIS LAWRENCE AYRES.
